Specification for Design.

Patented Mar. 29, 1921.

Application filed June 23, 1920. Serial No. 391,227. Term of patent 14 years.

To all whom it may concern:

Be it known that I, PALMER B. HEWLETT, a citizen of the United States, residing at Hollister, in the county of San Benito and State of California, have invented a new, original, and ornamental Design for Pulsator-Valve Casing for Milking-Machines, of which the following is a specification, reference being had to the accompanying drawing, forming part thereof.

On the drawings, Figures 1 and 2 are plan and side elevation views respectively of a pulsator valve casing embodying my design.

I claim:

The ornamental design for a pulsator valve casing for milking machines, as shown.
